means for operating said shuttle boxes, said operating means including a rotary shaft, a cam shaft mounted on the loom, a plurality of cams on said cam shaft, a gear on one end of the cam shaft, a segmental gear on the first mentioned shaft and being in mesh with the gear on the cam shaft and adapted to operate the cam shaft, pivoted lifting bars mounted on the frame of the loom and resting on said cams, vertically movable rods, adjustable connecting means connecting the lifting bars and vertically movable rods, lifting wires connected with the vertical rods, yieldable members connecting said wires with the loom frame, said wires being extended across the inner end of the shuttle boxes, and providing lifts for the fillings from the shuttles, and said lifting wires adapted to elevate the fillings of idle shuttles above the path of travel of the active shuttle, during the weaving of cloth.

2. In a device of the character described, the combination of a multi-shuttle loom and the shuttle boxes thereof, means for operating said shuttle boxes, said operating means including a rotary shaft, a cam shaft operated by said rotary shaft, a plurality of cams mounted on the cam shaft to move therewith, a plurality of vertical movable rods, bearings mounted on the loom and through which rods operate, normally horizontal wires being connected with the rods, coiled springs connected with said wires and being secured to the frame of the loom, said lifting wires adapted to move under the fillings from the shuttles, and said wires adapted to engage the fillings from idle shuttles, elevating the idle shuttle fillings above the path of travel of the active shuttles during the weaving of cloth.

ARTHUR S. DAWKINS.
